AR. TETRAHYDRO-NAPHTHYL THIOUREAS

Herbert A. Lubs and Arthur L. Fox, Wilmington,
Del., assignors to E. I. du Pont de Nemours &
Company, Wilmington, Del., a corporation of
Delaware

No Drawing. Application November 3, 1934,
Serial No. 751,283

3 Claims. (Cl. 260—125)

This invention relates to ar. tetrahydro-naphthyl thioureas and methods for preparing the same.

An object of this invention is to provide ar. 5 tetrahydro naphthyl thioureas which are new chemical compounds. A further object is to provide a method for preparing such new chemical compounds. Still other objects are to advance the art. Other objects will appear hereinafter.

10

15

These objects may be accomplished in accordance with the present invention which comprises reacting water soluble salts of acids and ar. tetrahydro-naphthylamines with alkali thiocyanates. The resulting products are ar. tetrahydro-naphthyl thioureas which are new chemical compounds. These new chemical compounds are valuable intermediates for the preparation of safety paper chemicals and dyestuffs.

In order to more clearly illustrate our invention and the preferred mode of carrying the same into effect, the following example is given:

30

Example I

The following ingredients were placed in a one liter flask and refluxed for 16 hours. 71.5 parts ar. tetrahydro beta naphthylamine, 300 parts water, 44 parts concentrated hydrochloric acid, 45 parts of ammonium thiocyanate. The ar. tetrahydro-beta-naphthylamine may be otherwise named as 2-amino-5-6-7-8-tetrahydro naphthalene. The amount of hydrochloric acid employed is just enough to bring the solution to the edge of congo acidity. The solution remained clear for about one hour and then became turbid as the thiourea began to form. After 16 hours, the flask was cooled rapidly with stirring and the ar. tetrahydro-beta-naphthyl thiourea solidified in the form of small shot-like crystals. The yield was 100 parts of crude material. The crude

material was recrystallized from 16 parts of alcohol giving a finely crystalline product melting at 174.6 to 175.8° C.

Analysis	Theory	5
N 13.21%	N=13.58%	
S 15.27%	S=15.52%	

The reaction takes place in accordance with the following equation:

Ar. tetrahydro-alpha-naphthylamine may be employed in the place of the ar. tetrahydro-beta-naphthylamine to produce the corresponding thiourea. Also, other acids which form water soluble salts with ar. tetrahydro-naphthylamines such as the hydrobromic, hydrofluoric, sulphuric, etc. may be employed in place of the hydrochloric. Other alkali thiocyanates such as the sodium and potassium thiocyanates may be employed in place of the ammonium thiocyanate. Also, other inert solvents or reaction media such as dilute alcohol, dilute acetone and the like may be employed in place of the water.

While we have disclosed the preferred form of our invention and the preferred mode of carrying the same into effect, it will be readily apparent to those skilled in the art that variations and modifications may be made therein, particularly in the relative proportions thereof without departing from the spirit of our invention. Accordingly, the scope of our invention is to be limited solely by the appended claims construed as broadly as is permissible in view of the prior art.

We claim:

1. An unsubstituted ar. tetrahydro naphthyl thiourea.
2. Ar. tetrahydro beta-naphthyl thiourea.
3. Ar. tetrahydro alpha-naphthyl thiourea.

HERBERT A. LUBS.
ARTHUR L. FOX.
